C. BADGER.

Grist Mill.

No. 28,434.

Patented May 22, 1860.

Inventor:

Charles Badger

UNITED STATES PATENT OFFICE.

CHARLES BADGER, OF EDGERTON, WISCONSIN, ASSIGNOR TO MELVILLE BADGER, OF SAME PLACE.

GRIST-MILL.

Specification of Letters Patent No. 28,434, dated May 22, 1860.

To all whom it may concern:

Be it known that I, CHARLES BADGER, of Edgerton, in the county of Rock and State of Wisconsin, have invented a new and useful Machine or Mill for Grinding and Bolt-ing Grain; and I do hereby declare that I know of no machine or grist-mill on which this is an improvement or could be regarded as such, except the ordinary grist-mills now 10 in common use throughout the country, which are, as far as my knowledge extends, always permanent and have never been made portable and do not involve to any extent the peculiar principles hereinafter 15 set forth; and I hereby declare that the following is a full and exact description thereof, reference being had to the accompanying drawings, and to the letters and figures of reference marked thereon, which is made a 20 part of this specification.

The nature of my invention consists in constructing a grinding mill in which geared machinery is firmly attached to a movable frame that is placed inside of the 25 principal frame that supports the bed or stationary stone and hopper—and which movable frame sustains at the upper end of the vertical shaft the runner or upper stone, and which interior frame, gearing attached 30 thereto, vertical shaft and runner, are ele-vated and lowered together whereby the stones are separated or brought nearer together to grind coarse or fine—and whereby the different parts of the gearing retain 35 their relative position undisturbed by such depression and elevation, also in combining the gear for driving the runner with the gear for driving the bolt so as to save the intervention and expense of additional gear 40 to drive the bolt, also in placing one gear wheel on the opposite side of the pinion on the vertical shaft from the gear that re-ceives the power and communicates the power to the vertical shaft and runner, 45 whereby the vertical shaft is kept from vi-brating, and giving great stability and steadiness of motion to light machinery.

The annexed drawings are a perspective view of the entire machine and its several 50 distinct parts, in which—

“A” represents the longitudinal elevation of the entire machine with the front side presented.

“F” represents the front side of the bolt 55 box.

“55” represents the curb which sur-rounds the bur stone within, over which “5” represents the hopper.

The power is designed to be applied by a knuckle, crank or wheel at “24”, which 60 is the extremity of an arbor or shaft, at the other extremity of which is a bevel cog wheel, from which the power is continued, transmitted and accelerated by a small cor-responding bevel wheel to an upright shaft, 65 as represented in the frame work by “25”. On the top of this upright shaft is properly fitted and secured the common bur grinding stone, after the manner of fitting in com-mon mills.

Wheel “18” is fitted on the left extremity 70 of the bolt-shaft, located, as ordinarily, in the bolt-box before specified. Motion is re-ceived from the bevel wheel on the upright shaft by a corresponding bevel wheel on 75 shaft “21”, at the other extremity of which is the small wheel “20” fitting the wheel “18”, to which wheel “18” is transmitted reduced motion for bolting. If found de-sirable, the main arbor or shaft “24” may 80 be extended and made the same shaft as “21”, through to the small wheel “20”, in which wheel “23” will be dispensed with.

“15” is a spout to conduct meal from the 85 curb into the bolt. “16” is a similar spout to conduct coarse meal and feed to a bag or box placed on platform “17”. At the mouth of spouts “15” and “16” are fitted certain slides by the regulation of and ad-justment of which meal can be conducted 90 either into the bolt, or into a bag or box on platform “17” at the option of the miller.

“B” represents a flour trough at the base 95 of the bolt box constructed nearly in the usual manner.

The shafts “21”, “24” and “25” with their accompanying wheels, are permanently secured in a frame as seen in Fig. 27, which frame is capable of an easy upward or downward motion, sliding on rods “57”. 100 This motion is obtained for the purpose of raising or lowering the bur stone, fitted on the top of the center shaft secured therein, and thereby setting the stone for coarse or fine grinding. This is done by means of the 105 lever “29”, the rod “30”, the nut and screws “32” and the wheel “33”.

For the purpose of more perfectly se-curing the upright shaft “25” from an up-ward motion in case of high speed, a shoul- 110

der is made on said shaft to bear against the middle beam passing through the upper part of said frame work, specified in Fig. 27, which shoulder is more clearly represented 5 in Fig. 59.

When the frame work is raised or lowered to any great extent, for the purpose of graduating the quality of the grinding, so that there is any danger of throwing the 10 bolt wheel "18" out of gear, the bolt wheel "18" can be raised or lowered to fit the small wheel "20" secured in the frame work, by means of different sized wedges fitted in the mortise above or below, through which 15 the lever or beam passes on which the bolt shaft rests.

The peculiar usefulness and advantages of this grist mill are represented as follows, to wit: First, any kind of power can be applied to it, such as horsepower, steam or water power, or power obtained from windmills. Second, power is applied, by this peculiar construction, for the purpose of grinding in the most simple and feasible 25 manner, and with but very little friction. Third, the peculiar and comprehensive construction of this mill by which the appropriate parts are brought into immediate contact and the whole machine, being a complete grinding and bolting mill, is reduced 30 to the least possible space. Fourth, the cheapness with which this grist mill, combining and comprehending all the advantages of any grist mill, can be built. Fifth, 35 the small amount of power required to overcome the friction in this mill and to produce motion sufficient for grinding and bolting. Sixth, its adaptation to the wants of all classes, in that the larger sizes can be used

as permanent mills attached to water or 40 steam powers, while the smaller sizes can be rendered portable, or otherwise, and adapted to the wants of extensive individual farmers and farming neighborhoods in dry land towns by the use of horsepower. Seventh, the grinding section can be readily so 45 constructed that it can be used with or without the bolting section, to suit the purchaser, simply by raising the left extremity of the bolt shaft by means of the lever on which it rests, and throwing wheels "18" and "20" 50 out of gear, or by separate construction thereof. This mill is intended however more particularly to supply the wants of the dry land towns of the west, by being made 55 portable and worked by horse power. The smaller sizes are designed and calculated to be operated by a two horse power.

What I claim as my invention and desire to secure by Letters Patent is:

1. The frame work "27", in which the gearing is located, in combination with the vertical shaft and runner when arranged substantially as described and for the purposes set forth.
2. The combination of the devices for driving the runner, with the devices for driving the bolt when constructed and operated substantially as described.
3. The cog gears on each side of the pinion, in combination with the pinion and shaft in Fig. 27, substantially as described and for the purpose set forth.

CHARLES BADGER.

In presence of—

CHARLES L. BROWN,
JAMES H. HILL.
